UNITED STATES PATENT OFFICE.

COLUMBUS H. CHRISTIAN, OF ATLANTA, AND EARL H. HUTCHESON, OF AUGUSTA,
GEORGIA.

RAILWAY-CROSSING.

1,015,541.

Specification of Letters Patent.

Patented Jan. 23, 1912.

Application filed July 10, 1911. Serial No. 637,823.

To all whom it may concern:

Be it known that we, COLUMBUS H. CHRISTIAN, a citizen of the United States, and resident of Atlanta, in the county of Fulton and State of Georgia, and EARL H. HUTCHESON, a citizen of the United States, and resident of Augusta, in the county of Richmond and State of Georgia, have invented certain new and useful Improvements in Railway-Crossings, of which the following is a specification, reference being had to the accompanying drawings.

The invention relates to railway crossings of that description which are formed of metallic castings placed at the intersection of two tracks to form continuations of the rails past the intersection.

In many of the crossings in common use, to make the connections with the ends of the rails, it is necessary to cut the ends of the rails to particular shapes to fit the rail connections of the crossing.

One of the objects of the present invention is to provide a crossing that can be joined to the ends of rails that have been cut squarely across.

It also has for its object the provision of means that will firmly hold the connected ends of the rails in place, which can be easily embedded in the road-bed so as to be held securely against displacement, and in which the flange-block can be readily replaced when it becomes worn.

The invention consists in the novel construction, combination and arrangement of parts, hereinafter described, pointed out in the appended claims and illustrated in the accompanying drawings.

In the drawings, in which similar reference characters designate corresponding parts, Figure 1 is a plan view, broken away in parts, of a crossing embodying the invention. Fig. 2 is a perspective view of the main part of the crossing, the flange-block being removed. Fig. 3 is a perspective view of the flange-block. Fig. 4 is a sectional view on the line 4-4 of Fig. 1. Fig. 5 is a plan view, broken away in parts, showing a modification of the invention. Fig. 6 is a plan view of the flange-block of the modification. Fig. 7 is a cross-section of the same.

As shown in Figs. 1 to 4, inclusive, the crossing is of a generally rectangular formation and is adapted to tracks intersecting

each other at right-angles. The base plate 55 supporting the crossing is of considerable area so as to give an extensive foundation when the crossing is embedded in the road-bed and enables it to withstand the loads and shocks of passing vehicles. Integral with 60 the base plate 1 and projecting from its upper surface is the seat-box 2 with its bottom elevated somewhat above the surface of the bed-plate. Passing through the bottom of the seat-box and the bed-plate in a 65 central position is the cylindrical opening 3. The excessive thickness of the metal in the bottom of the seat-box and adjacent part of the bed-plate compensates for the metal cut away to form the opening 3. In the 70 lower outer edge of each wall 4 of the seat-box is a horizontal groove 5 to receive the base 6 of an abutting rail, extending upwardly from the groove is the vertical slot 7 to receive the web 8 of the rail, and at the 75 upper end of the slot the top edge of the wall is recessed, as at 9, to receive the crown 10 of the rail. By means of this construction the abutting end of the rail can be cut off at right angles to its length and the 80 squared end without any special shaping fitted into the opening in the wall formed by the horizontal groove 5, the vertical slot 7 and the recess 9. The base 6 engaging with the groove 5 will hold the end of the rail 85 against upward movement, and the web 8 engaging the slot 7 will prevent any sidewise movement of the end of the rail. Projecting outwardly from the wall 4 adjacent to the slot 7 is the lug 11 bolted to the web 8 90 of the rail by the bolts 12, which prevents any longitudinal movement of the rail relative to the crossing. In the upper edge of each wall 4 adjacent to the recess 9 and along the side of the end of the rail is the 95 groove 13 to receive the flange of a passing wheel. Fitted in the seat-box 2 is the flange-block 14 with its surface flush with the treads of the adjacent rails and the top edges of the walls 4 of the seat-box. On the surface of the flange-block are the intersecting treads 15 forming continuations of the treads of the adjoining rails, and along the sides of these treads extend the intersecting grooves 16 to permit the passage of the flanges of the 100 wheels traveling on the treads. The grooves 16 register with the grooves 13 in the walls of the seat-box. The surface of the flange-

block outside of the treads 15 is corrugated to prevent slipping of horses' feet. From the under side of the flange-block is the cylindrical stud 17 fitting the cylindrical opening 3 in the bottom of the seat-box. This stud fits the cylindrical opening closely and holds the flange-block against the strain of passing wheels and prevents the strain from coming against the walls of the seat-box.

Upward displacement of the flange-block is prevented by screws 18 passing through the same into the bottom of the seat-box. It is evident that a worn flange-block can be readily replaced by a new one by loosening the screws 18. As shown by full lines in Fig. 2 and dotted lines in Fig. 4, there is an enlargement 19 at the upper end of the screw-hole in the bottom of the seat-box for one of the screws 18. After the screw in this particular hole has been removed a hook can be inserted through the screw-hole in the flange-block into the enlargement 19 to facilitate the removal of the flange-block.

By the foregoing construction a crossing is provided which can be readily and easily put in place and secured, one to which rails with square-cut ends can be easily attached, one which will sustain wear and in which worn parts can be readily replaced.

In the modification shown in Figs. 5 to 7, inclusive, the crossing is adapted to tracks intersecting at acute angles. On the base-plate 21 and integral with the same is the circular seat-box 22. In this seat-box is seated the circular flange-block 23 with the flange-grooves 24 in its face intersecting each other at acute-angles. Projecting from the periphery of the flange-block are the spurs 25 extending through openings in the wall of the seat-box. The ends of these spurs are cut square across to meet the square-cut ends of the rails 26. The rails are secured to the ends of the spurs by the lugs 27 extending from the wall of the seat-box 22 and bolted to the ends of the rails.

Having thus described our invention, what we claim and desire to secure by Letters-Patent is,

1. In a railway crossing, a base-plate, a seat-box integral with the base-plate provided with a central opening in its bottom and having openings in its side-walls, a flange-block fitted in the seat-box provided with rail-treads on its upper surface, a stud 55 projecting from the under side of the flange-block and fitting in the central opening in the bottom of the seat-box, rails resting at their ends on the base-plate forming with the rail-treads on the flange-block continuous tracks through the openings in the

side-walls of the seat-box, and means for securing the ends of the rails in place.

2. In a railway crossing, a base-plate, a seat-box on said base-plate integral with the same with openings in its walls to receive the ends of rails, rails with square-cut ends entering said openings in the walls of the seat-box, spurs projecting from the walls of the seat-box secured to the ends of the rails, a flange-block fitted in said seat box provided with intersecting treads on its face to form continuations of the treads of the rails and having flange-grooves adjacent to the treads, and a stud projecting from the under side of the flange-block and engaging the bottom of the seat-box.

3. In a railway crossing, a base-plate, a seat-box on said base-plate integral with the same with its wall having an opening formed of a groove to receive the base of a rail, a slot extending vertically upward to receive the web of the rail and a recess at the top of the slot to receive the crown of the rail, a rail having its end cut-square across engaging said opening, means for securing the end of the rail to the seat-box, a flange-block seated in said seat-box having intersecting treads on its face to form continuations of the treads of the rails attached to the seat-box, and a stud projecting from the under side of the flange-block into the bottom of the seat-box.

4. In a railway crossing, a base-plate, a seat-box on said base-plate integral with the same with its wall having an opening formed of a horizontal groove to receive the base of the rail, a slot extending vertically upward from the horizontal groove to receive the web of the rail and a recess at the upper end of the vertical slot to receive the crown of the rail, a rail with a square-cut end entering said opening, a spur projecting outwardly from the wall of the seat-box and attached to the rail, and a flange-block seated in said seat-box having intersecting treads on its face to form continuations of the treads of the rails attached to the seat-box.

In testimony whereof we hereunto affix our signatures in the presence of two witnesses.
